[57] CLAIM

The ornamental design for an antique car body, as shown and described.

DESCRIPTION

FIG. 1 is a side perspective view of an antique car body
showing my new design;

FIG. 2 is a side perspective view thereof, opposite to

FIG. 3 is a front perspective view thereof; and

FIG. 4 is a rear perspective view thereof;

The interior or passenger seating area of the antique car body forms no part of the present invention.

FIG. 1.

FIG. 2.
